UNITED STATES PATENT OFFICE.

ALFRED S. HOGGATT, OF BENTON HARBOR, MICHIGAN.

AUTOMATIC CROSSING GUARD.

Application filed March 19, 1924. Serial No. 700,306.

To all whom it may concern:

Be it known that I, ALFRED S. HOGGATT, a citizen of the United States, resident at Benton Harbor, in the county of Berrien 5 and State of Michigan, have invented a new Automatic Crossing Guard, of which the following is a specification.

This invention relates to improvements in automatic railway crossing gates and has 10 as its general object to provide a crossing gate and means for automatically elevating and lowering the same in accordance with the passage of trains over the crossing, so that the services of a watchman at the crossing 15 will not be required.

Another object of the invention is to provide a simple mechanism, operated by a train approaching the crossing from either direction, for effecting a lowering of the 20 crossing gate or gates before the train reaches the crossing, and likewise effecting an automatic raising of the gate or gates after the train has passed the crossing, the the arrangement being such that after a 25 train has passed the crossing, the parts of the mechanism will be automatically reset for subsequent operation.

In the accompanying drawings:

Figure 1 is a vertical longitudinal section view, partly in elevation, illustrating 30 one of the trip mechanisms constituting a part of the invention and one of which mechanisms is located at each side of the crossing.

Figure 2 is a similar view illustrating one 35 of the crossing gates and the means provided for raising and lowering the same.

Figure 3 is a view similar to Figure 1, in detail, illustrating in full and dotted 40 lines, the manner in which the two companion trip mechanisms are operated in consonance with each other.

Figure 4 is a detail view, partly in elevation and partly in section, illustrating a 45 portion of the mechanism.

Referring first to Figure 2 of the drawings, the crossing gate is indicated in general by the numeral 1, and the said gate is fixed upon a shaft 2 which is rotatably 50 mounted in the upper portion of a housing 3 which, in turn, is embedded at its lower portion in a foundation 4 of concrete or other material laid in the roadbed at the side of the crossing. It will be understood 55 at this point, that a pair of the gates will

be employed where the crossing is relatively narrow, and two pairs will be employed where the crossing is comparatively wide, the structure shown in Figure 2 being identical for each of the gates or, if desired, a connection of any suitable nature may be employed between two companion gates so that only one of the raising and lowering mechanisms need be employed and associated with one of said gates. However, such arrangements are not illustrated in the drawings as they constitute no part of the invention and are to be left to the judgment of those manufacturing and erecting the gates and their associated mechanisms. 60 Fixed upon the shaft 2 within the housing 3, is a crank disc 5 carrying a crank pin 6 to which is connected the upper end of a link 7, the lower end of the said link being pivotally connected, as at 8, with the upper end of a rock arm 9 pivotally mounted as at 10, upon a bearing 11 within the said housing 3. The arm 9 is formed in its lower portion and below the pivot pin, with a longitudinal slot 12, and a member 13 is 65 suitably mounted upon this portion of the arm to work longitudinally in the slot, and a cable 14, to be hereinafter more fully described, is secured in any suitable manner to the said member 13, as best shown in Figure 2. The cable 14 has its stretches 70 which extend from either side of the member 13, passed over pulleys 15 mounted within the housing 3, and the said stretches are then led through suitable conduits 16 75 formed in the foundation 4 and to other parts of the mechanism which will presently be described. At this point it will be understood that when a pull is exerted upon one stretch of the cable, for example that 80 stretch extending toward the right in Figure 2 of the drawings, the lever arm 9 will be rocked about its pivot 10 to substantially the dot and dash line position shown in Figure 2, thereby exerting a downward pull 85 upon the link 7 and causing the shaft 2 to rotate in a direction to lower the gate 1. On the other hand, when a pull is exerted upon the other stretch of the cable 14, or, in other words that stretch which extends toward 90 the left in the said Figure 2, the arm 9 will be rocked in a reverse direction to assume substantially the dot and dash line position shown in the said figure, in assuming which 95 position, a downward pull will also be ex- 100 105 110

21
ereted upon the said link, as in the former instance so as to effect lowering of the gate. Trip mechanism which is illustrated in Figure 1, and indicated in general by the reference numeral 17, and which mechanism will presently be more specifically described, is provided, and one of said mechanisms is located at each side of the crossing and some distance from the gate or gates to be controlled thereby, and in the operation of the trip mechanism, which is presumed to be beyond the gate shown in Figure 2 and in a direction toward the right, a pull will be exerted upon the first mentioned stretch of the said cable 14, as described above. On the other hand, the other trip mechanism at the other side of the crossing and beyond the same toward the left in Figure 2, will, when actuated, effect a pull upon the left hand stretch of the cable in Figure 2 to effect lowering of the gates, likewise as described above, it being understood that under each condition of operation, the lever arm 9 and link 7 will initially be in the full line or normal position shown in Figure 2. It will also be evident that a pull upon either stretch of the cable 14, when the arm 9 and link 7 are in the dotted line or dot and dash line position in said figure, will result in the parts being restored to their normal or full line position.

Referring now more particularly to Figures 1 and 3 of the drawings, which figures best illustrate the trip mechanism, the numeral 18 indicates a foundation which is laid in the roadbed beyond the crossing and which foundation is so constructed as to house the component parts of the trip mechanism as shown in the said Figures 1 and 3. The trip mechanism includes a trip member 19 which is in the form of a metallic beam suitably pivotally mounted at one end, as at 20, in the foundation 18 and having its upper surface 21 inclined upwardly from its opposite ends to a point substantially midway between its ends, this gentle rise in the engaging surface of the trip member permitting of an actuating element (not shown) upon the locomotive of a train travelling upon the railway, engaging the trip member and riding thereover without injury to the said members, it being understood that the intermediate portion of the trip member has its engaging surface sufficiently elevated to be presented for engagement by the said element upon the locomotive and in a manner to effect downward swinging movement of the trip member upon engagement of the locomotive-carried element therewith. A spring 22 is mounted at its lower end in the foundation 18 and at its upper end is engaged with a stud 23 upon the under side of the trip member 19 between its intermediate portion and its pivoted end 20, and this spring is of sufficient strength to nor-

mally support the trip member in an elevated position as shown in full lines in Figure 3, depression of the trip member when engaged by the locomotive-carried actuating element, being, of course, against the tension of the said spring. In order to limit the upward movement of the trip member under the influence of the spring 22 and definitely determine the position of the trip member under normal conditions, an abutment 24 is arranged upon the foundation at one end of the housing therein for the parts of the trip mechanism, and overhangs the free end of the said trip member 19, as clearly shown in Figure 1. A lifting or pick-up rod 25 is pivotally suspended at its upper end, as at 26, from the underside of the trip member 19 at the intermediate portion thereof, and a spring 27 is connected at one end to the said arm below the pivot 26 and at its other end to the under side of the said trip member, the spring yieldably urging the arm about its pivot in one direction and more specifically, toward an actuating means for the cable 14, which actuating means or mechanism is indicated in general by the numeral 28.

The cable actuating mechanism 28 comprises a standard 29 which is mounted within the housing of the foundation 18 in juxtaposition to the pick-up rod 25, and suspended for back and forth swinging movement within the upright 29, by means of a pivot 30, is a lever arm 31 to the lower end of which is connected, as at 32, one end of the cable 14, the cable being led over pulleys 33 and through a conduit 34 in the foundation 18, to the gate actuating mechanism as illustrated in Figure 2. The lever 31 is provided a normally horizontally extending arm 34 opposite the pivot 30, and this arm terminates in a rounded head 35 designed, under conditions to be presently explained, to seat in a notch 36 formed in the adjacent side of the pick-up rod 25. Said arm 34 supports, in turn, a second arm which is indicated by the numeral 37 and which extends upwardly from the arm 34 and thence horizontally above the same in parallel relation thereto and terminates in a rounded head 38 corresponding to the head 35, and likewise engageable, under conditions to be hereinafter explained, in the notch 36. Above its pivot 30, the lever arm 31 is provided with an arcuate head 39 operating in an arcuate casing 40 supported at the upper end of the standard 29 and engaged at its opposite ends by compression springs 41 which are housed within the ends of the casing and, due to the opposing pressure exerted thereby, normally hold the arm 31 in vertical position as shown in full lines in Figures 3 and 4 of the drawings. At this point, it will be observed that normally the rounded heads 35 and 38 of the arms 34

and 37 are presented to that side of the pick-up rod or bar 25 in which the notch 36 is formed, the head 38 being located opposite the said notch but out of engagement 5 therein, and the head 35 being in direct engagement with the said edge of the bar, due to the pull exerted upon the bar by the spring 27. The coaction of these parts will be explained in the description of the operation of the mechanism which will be hereinafter given.

To control the bar 25 under conditions to be presently explained, a cable 42 is connected at its opposite ends to the bars 25 of the associated trip mechanisms and is led about pulleys 43 arranged within the respective foundations 18, and clamped at each respective end portion in a sleeve 44 pivotally connected with the lower end of an angle lever 45, the said lever being pivotally mounted at the juncture of its arms, as at 46, upon a bracket arranged within the said housing of the foundation. The other arm of the angle lever, indicated by the 25 numeral 47, extends normally substantially horizontally and beneath the lower end of the pick-up bar 25, and it will be evident by reference to Figure 3, that the cable 42 has a stretch extending over the pulleys 33 and 30 between the two associated trip mechanisms.

Assuming that the parts are in the normal positions illustrated in full lines in Figures 2 and 3 of the drawings, in which positions of the parts the trip members 19 will 35 be elevated and the gates 1 will be raised, the operation of the mechanism is as follows, assuming that a train is approaching the crossing from the right in the said figures, reference being also had, in this connection, to Figure 1. As the train passes over the trip member 19 at the right of the crossing, the said member will be depressed against the tension of the spring 22, thereby moving the pick-up rod 25 downwardly 40 until it assumes the lowered broken line position shown in Figure 3, at the right, the right hand trip mechanism in this figure being indicated by the reference letter R and the left hand trip mechanism by the reference letter L. In this movement of the arm, the notch 36 will be lowered to a position 45 opposite the head 35 at the end of the arm 34 and the angle lever 45 will be rocked, due to the downward pressure exerted by 50 the rod 25 against the arm 47 of said lever, thereby slackening the stretch of the cable 42 between the connection 44 and its end which is connected to the said bar 25. The spring 27 is, in the meantime, exerting a 55 pull upon the bar 25 to hold the same in the direction of the head 35 and as the engaging element upon the locomotive of the train rides past the trip member 19, the spring 22 will act to return the trip member to its 60 elevated or normal position, at which time

the head 35 will be in engagement in the notch 36, and the upward movement of the bar 25 will effect a rocking movement of the cable actuating lever 31. In this movement of the lever 31, the lever will assume 70 the dotted line position shown in Figure 3, at the right, the arms 34 and 37 being at this time swung upwardly through the upward movement of the pick-up bar 25. In this movement of the lever 31, a pull will 75 be exerted upon the cable 14, effecting rocking movement of the lever 9 to exert a pull upon the link 7 and move the gate or gates 1 to lowered position. This pull upon the cable will likewise result in a movement of the lever 31 of the trip mechanism L in Figure 3, to the dotted line position shown in said figure. The parts will maintain the positions which they have now assumed until the train has reached the other trip member 80 19 of the trip mechanism L, when said member 19 of the said left hand trip mechanism will be depressed to lower the respective pick-up bar 25 and actuate the respective angle lever 45 to exert a pull upon the cable 42 in the reverse direction to that above described and thereby swing the pick-up rod 25 of the trip mechanism R in Figure 3, out of engagement with the head 35 at the 85 end of the arm 34 and permitting the lever 31 to return to its normal position under the influence of the spring 41 associated therewith. At the same time, the pick-up rod 25 of the trip mechanism L will pick up the end 38 of the arm 37 of the respective lever 31 and, through rocking movement of the lever 31, a pull will be exerted upon the cable 14 toward the left in Figure 3 and likewise in Figure 2, so as to again rock 90 the lever 9 but in an opposite direction so as to exert an upward thrust upon the link 7 and raise the gate or gates 1. Of course, in the instance of a train approaching the crossing from the left, the same operation 95 will take place except that the left hand trip member 19 or, in other words, the trip member of the trip mechanism L, in Figure 3, will be the first to be depressed to effect a lowering of the gate or gates.

Having thus described the invention, what 115 I claim is:

1. In an automatic railway crossing gate, in combination with the gate to be operated, counterpart trip mechanisms located oppositely beyond the gate, each mechanism comprising a depressible trip member, means yieldably resisting depression thereof and for returning the same to normal position when depressed and then relieved of pressure, a lever having an outstanding arm, operative connection between the levers of the two trip mechanisms and the gate for operating the latter when either lever is actuated, and means actuated through depression of said member and coacting with the 125

arm of the respective lever to actuate the latter upon return movement of the trip member to normal position.

2. In an automatic railway crossing gate, in combination with the gate to be operated, counterpart trip mechanisms located oppositely beyond the gate, each mechanism comprising a depressible trip member, means for returning the trip member to normal position after depression, a lever, operative connection between the levers of the two trip mechanisms and the gate for operating the latter when either lever is actuated, and means actuated through depression of the trip member and coacting with the respective lever to actuate the latter upon return movement of the trip member to normal position.

3. In an automatic railway crossing gate, in combination with the gate to be operated, counterpart trip mechanisms located oppositely beyond the gate, each mechanism comprising a depressible trip member, means yieldably resisting depression thereof and for returning the same to normal position when depressed and then relieved of pressure, a lever having outstanding upper and lower arms, operative connection between the levers of the two trip mechanisms and the gate for operating the latter when either lever is actuated, and a pick-up member suspended from the trip member and having a seat therein for the selective engagement of the ends of the arms of the lever to effect actuation of the lever upon return movement of the trip member to normal position.

4. In an automatic railway crossing gate, in combination with the gate to be operated, means associated with the gate to effect raising and lowering thereof, counterpart trip mechanisms located oppositely beyond the gate, each of said mechanisms comprising a depressible trip member, means yieldably resisting depression thereof and for returning the same to normal position when depressed and then relieved of pressure, a lever, a connection extending between the levers of the trip mechanisms and operatively connected at an intermediate point with an element of the raising and lowering means for the gate, and means carried by the said trip member of each trip mechanism for coaction with the said lever to actuate the same upon return movement of the trip member to normal position, whereby successive depression of the trip members of the two mechanisms will effect shifting of the said connection in opposite directions to

effect operation of the gate raising and lowering means to lower and raise the gate. 60

5. In an automatic railway crossing gate, in combination with the gate to be operated, means associated with the gate for raising and lowering the same when an element of said means is operated, counterpart trip mechanisms located oppositely beyond the gate, each of said mechanisms comprising a depressible trip member, means yieldably resisting depression thereof and for returning the same to normal position when depressed and then relieved of pressure, a lever associated with each trip mechanism and including upper and lower arms, a pick-up bar suspended from each trip member and positioned to coact with the ends of the arms of the respective lever, each bar having means for coaction with the ends of the arms of the respective lever when the bar is lowered through depression of the respective trip member and then moved upwardly at the time of return of the trip member to normal position, and a connection extending between the said levers and operatively connected at an intermediate point to the said element of the raising and lowering means for the gate. 75 80

6. In an automatic railway crossing gate, in combination with the gate to be operated, means associated with the gate for raising and lowering the same when an element of said means is operated, counterpart trip mechanisms located oppositely beyond the gate, each of said mechanisms comprising a depressible trip member, means yieldably resisting depression thereof and for returning the same to normal position when depressed and then relieved of pressure, a lever associated with each trip mechanism and including upper and lower arms, a pick-up bar suspended from each trip member and positioned to coact with the ends of the arms of the respective lever, each bar having means for coaction with the ends of the arms of the respective lever when the bar is lowered through depression of the respective trip member and then moved upwardly at the time of return of the trip member to normal position, a connection extending between the said levers and operatively connected at an intermediate point to the said element of the raising and lowering means for the gate, and means actuated through the downward movement of each pick-up bar to effect displacement of the other bar at the time the first mentioned bar is active. 100 105 110

ALFRED S. HOGGATT.
